UNITED STATES PATENT OFFICE.

JOSEPH C. THEBERATH, OF CLEVELAND, OHIO, ASSIGNOR, BY MESNE ASSIGNMENTS,
TO THE STANDARD PARTS COMPANY, OF CLEVELAND, OHIO, A CORPORATION OF
OHIO.

WELDING-TORCH.

1,264,581.

Specification of Letters Patent. Patented Apr. 30, 1918.

Application filed August 17, 1916. Serial No. 115,412.

To all whom it may concern:

Be it known that I, JOSEPH C. THEBERATH, a citizen of the United States, and a resident of Cleveland, county of Cuyahoga, and State of Ohio, have invented a new and useful Improvement in Welding-Torches, of which the following is a specification, the principle of the invention being herein explained and the best mode in which I have 10 contemplated applying that principle, so as to distinguish it from other inventions.

The present improvements relate to welding torches of the so-called oxy-acetylene type, and still more especially to the construction of the tips of such torches. In this type of torch, as at present constructed, the tip-holder, which has a conical plug at its inner end for making a gas and watertight joint with the appropriate connections 15 in the body of the torch, is in effect a unitary structure, being made up of a central portion with an outer shell that forms the water space for cooling, while the tip forms an integral extension of such core. It accordingly is not only inconvenient, if not impossible, to clean the passages through such tip when they become clogged, but if it is desired to change one tip for another, the entire holder structure has to be removed, 20 involving in the replacement thereof, or in the substitution of another, the troublesome fitting together of the conical plug at the inner end of the structure with the complementary seat in the main body portion of 25 the torch, so as to secure proper alinement of the various passages, as well as a tight fit.

The object of the present invention is to provide a torch holder so constructed, that, while it has the same conical plug which 30 may be separated from the seat in the torch body, if desired, it is nevertheless possible to effect the detachment of the tip, proper, without disconnecting the parts at the point just named, or disturbing the connections 35 through such joint. A further object is to insure adequate cooling of the tip holder close up to the tip, while yet another object is to provide means for properly distributing the gases to the several apertures in the 40 tip, thereby insuring an equable heating effect, as is quite essential where the tip is provided with a series of alined apertures designed to provide an elongated flame. To 45 the accomplishment of the foregoing and related ends, the invention, then, consists of

the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Figure 1 is a central axial cross section of the forward end of a torch body, showing attached thereto a tip and tip holder embodying my present improvements; Figs. 2, 3 and 4 are transverse sectional views of the same, the planes of the sections being indicated by the lines 2—2, 3—3 and 4—4, respectively, Fig. 1; Fig. 5 is an end elevation of the device as viewed from the right in Fig. 1; Fig. 6 is a central axial section of the tip by itself, the plane of the section being at right angles to that of Fig. 1, is indicated by line 6—6 on said figure; and Fig. 7 is a perspective of a baffle, or distributor member, that forms a feature of the device.

As indicated, only the forward end of the body 1 of the torch is shown in the drawing, such body being of more or less familiar construction, the only part of particular interest in the present connection being the cone-seat, or socket 2, wherewith the various ducts or ports 3, 4 and 5 that supply oxygen, acetylene and water, respectively, to the tip holder, are suitably connected. These ducts, it will be understood, are all contained within the body of the torch, suitable flexible leads, (not shown) being connected thereto at the other end of such body.

The tip-holder proper comprises a core member 10 formed with a conical plug or head 11 at one end adapted to seat in the socket 2 in the forward end of the torch body 1, such head having a central, axial aperture 12 adapted to communicate with the oxygen and acetylene supply ducts 3 and 4 through passages 13 and 14, respectively, 95 and also two longitudinally extending passages 15, one on each side of such axial passage, which are adapted to communicate with the water supply and exhaust ducts 5, respectively.

Such head is formed with a shoulder 16 on its forward face and the opposite end of the core member is formed with an enlargement 17 so that a tubular shell 18, when tightly fitted over such enlargement 100

and against such shoulder, provides two water circulating chambers 19, one on each side of the core proper. Channels 20, one on each side of such core at the forward end 5 of these chambers, shown in Fig. 1, serve to connect the same and permit the water to circulate in the fashion desired.

Removably fitted over the shell and adapted to bear against the outer portion of the 10 shoulder on the core head, is a sleeve 25 internally threaded at its inner end to engage internal threads in the torch body and provided with a polygonal portion 26 to receive a wrench, or like tool. By means of such 15 sleeve the core, once its head is properly located in the socket, may be firmly secured in place, as will be obvious.

The torch tip 30, proper, is in general of 20 familiar construction, being provided with a chamber 31 from which extend a series 25 of passages 32 that are of different lengths, the end of the tip being formed with a series of steps 33, as shown in Figs. 1 and 6. Instead, however, of making such tip an integral part of the core, as heretofore, I make 30 the same a separate member, having its rear face fitted tightly against the front end of such core and provided with an external shoulder 34 for the purpose presently to be described.

In the chamber 31 is removably held a member 35 in the form of a bar, having a diamond-like cross section, as shown in Fig. 6, such bar being shown in perspective in Fig. 35 7. The gases as they are discharged into the chamber through the central passage 12 in the core 10, strike this bar, which divides and deflects the stream so as to equalize the pressure at all of the discharge orifices 32, 40 and thus insure a steady and uniform flame across the entire stepped edge of the tip 30.

To secure the tip in place a flanged cap 36 is provided, being adapted to engage the shoulder 34 on the inner end of the tip and 45 being internally threaded to engage external threads on the sleeve 25. It will be obvious that by means of this cap the tip may be firmly secured onto the end of the holder, that is, against the end of the core member 50 with its surrounding shell, and yet if it be desired to remove the tip, either to clean the same, or replace it with another, the connection between such holder's inner end and the cone-socket in the main body of the torch 55 need not be disturbed.

The advantage in this construction over the prevailing one is self-evident, and the same is true as to the function of the deflector member 35 in the chamber in the tip proper, which insures a uniform distribution 60 of gases to all of the orifices in such tip. Finally, by reason of the water-circulating

chambers 19, I am enabled to carry the cooling liquid to the very extremity of the tip holder and so maintain even the tip itself at 65 a temperature below that at which it is likely to become damaged by the heat.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a device of the character described, the combination with a burner tip having a chamber and a plurality of discharge orifices leading therefrom; of an elongated baffle in 80 said chamber disposed close to and in line with such orifices, and adapted to distribute the fuel more or less equally between the same.

2. In a device of the character described, 85 the combination with a torch body having a socket at one end with a plurality of ports for gaseous fuel and cooling liquid; of a member formed with a head adapted to fit such socket and having a through central 90 passage adapted to register with such fuel ports and two lateral chambers in communication with each other at their outer ends adapted to register with such liquid ports; a sleeve surrounding said member and engaging the head thereon, said sleeve being individually threaded in said body, whereby 95 said member may be secured to the latter in proper relation to such ports; a burner tip adapted to abut against the outer end of said member; and a cap, externally threaded on the corresponding end of said sleeve, adapted to detachably clamp said tip in place.

3. In a device of the character described, 105 the combination with a burner tip having a chamber and a plurality of aligned discharge orifices leading therefrom; of an elongated baffle in said chamber disposed in line with such orifices and adapted to distribute the fuel more or less equally between the same. 110

4. In a device of the character described, 115 the combination with a burner tip having a chamber and a plurality of aligned discharge orifices leading therefrom; of an elongated baffle of diamond cross-section in said chamber disposed in line with such orifices and adapted to distribute the fuel more or less equally between the same.

Signed by me, this 15 day of Aug. 1916.

JOSEPH C. THEBERATH.
